UNITED STATES PATENT OFFICE

LOUIS A. BITTORF, OF STERLING, ILLINOIS, ASSIGNOR TO NATIONAL MANUFACTURING COMPANY, OF STERLING, ILLINOIS, A CORPORATION OF ILLINOIS

DOOR HOLDING DEVICE

Application filed December 18, 1930. Serial No. 503,166.

My invention relates to door-holding devices of that general type adapted to latch and retain swinging doors, and the like, in predetermined open position preventing accidental closing of the same. While my invention is adapted to various kinds of doors of this character, it is well suited for garage, or similar, doors.

One of the objects of my invention is to provide a simple and inexpensive device of the foregoing character which is positive in action and which is adapted to automatically secure and hold a swinging door against closing due to any jar, force or shock when the door has been moved to a predetermined open position, but which provides for ready and convenient release of the door when it is desired to close the same.

Another object is to provide a strong and durable door holding device which includes an arm swingably carried by the door and movable through a keeper device stationarily supported by the door frame, which keeper device embodies latch means engageable with the arm for holding the door in its open position; and the latch means is releasable by means carried by the swinging arm and conveniently located for actuation for closing of the door.

Other objects and advantages will become apparent as this description progresses and by reference to the drawings wherein,—

Figure 1 is a partial elevational view of a door structure (the upper portion cut away) embodying my invention, the parts of such structure being shown in door-closed position;

Fig. 2 is a view of the structure of Fig. 1 taken substantially at the position indicated by line 2—2 of Fig. 1, and showing the door and the door holder part in full lines in their open position and in dotted lines in their closed position;

Fig. 3 is an enlarged side elevational view of the outer or free end of the door holding arm;

Fig. 4 is an enlarged vertical sectional view through the keeper device and the outer or free end of the door holding arm, and showing the parts in their latched position;

Fig. 5 is a view similar to Fig. 4 except showing the parts in an unlatched position;

Fig. 6 is a view taken substantially on line 6—6 of Fig. 4;

Fig. 7 is a horizontal section taken substantially on line 7—7 of Fig. 6;

Fig. 8 is a longitudinal sectional view similar to Fig. 4 but showing a modified form of structure embodying my invention;

Fig. 9 is a section taken substantially on line 9—9 of Fig. 8;

Fig. 10 is a longitudinal section through another modified form of keeper embodying my invention, which view is taken substantially on line 10—10 of Fig. 11;

Fig. 11 is a rear elevational view of the structure shown in Fig. 10; and

Fig. 12 is a horizontal section taken substantially on line 12—12 of Fig. 11.

It will be understood that while I have chosen to illustrate my invention in connection with the structure shown in the drawings, I do not wish to be limited to the same since it is obvious that my invention has utility in any installation where it is desired to automatically latch the swinging member in a predetermined open position and in condition for ready and convenient release of the latch when it is desired to close the swinging member.

Referring particularly to the form shown in Figs. 1 to 7, inclusive, the doorway is formed by top and side frame members 20, 21. Doors 22, 22' are swingably mounted upon the side frame members 21 by means of hinges 23 (only one shown). These doors are of a type well adapted for garages and my invention provides the following means for latching and holding the doors in open position to avoid closing of the same by drafts, gusts of wind, jars, shocks, etc., when a vehicle is being moved into or removed from the garage through its doorway.

Referring to the embodiment of Figs. 1 to 7, inclusive, an arm 24 is mounted for horizontal swinging movement on a bracket 25 which is secured to the inner surface of the door 22. This arm is of inverted U-shape in cross section, and it pivotally supports (as at 26) within its U-section an unlatching bar

27 which is swingable about the pivot 26 by means of a chain 28 to project its outer end 27^a upwardly through a longitudinal, notched opening 24^a in the top part of the 5 arm just inwardly of the abutment member 29. This abutment member 29 is held between the U-sides of the arm at its outer end by means of rivets, or the like, 30 and it is provided at its bottom with a shelf-like ex- 10 tension 29^a which is adapted to be engaged by the flat-bottom end portion 27^b of the unlatching bar 27 to limit the downward or released position of such bar.

The arm 24 is supported and guided by a 15 keeper 31 the vertical web 31^a of which has an opening 32 through which the arm slidably passes. The horizontal web 31^b of this keeper is secured to the top frame member 20, preferably, at the position illustrated in 20 Fig. 1, and the location of this keeper is such that when the door is fully opened, the flat side 29^b of the stop abutment 29 seats flat against the rear side of the keeper above the keeper opening 32, thus limiting the opening 25 movement of the door.

The door is automatically latched in its full open position by a latch plate 33 which is approximately the same size and shape as the vertical web 31^a of the keeper; and this 30 plate has an opening 34 therein of substantially the same size as the keeper opening 32 and through which the arm 24 also passes. This latch member is reciprocably mounted on the vertical keeper web by means of a 35 plurality of vertically-extending slots 35 through which headed pins or rivets 36 (carried by the keeper 31) project. This latch plate is movable with sufficient freedom that it always tends to fall downwardly by gravity 40 to the latching position shown in Figs. 4 and 6.

When the door is in its closed position (Fig. 1) the upper surface of such arm holds the latch plate 33 elevated. The outer end 45 of the door arm 24 along the opening 24^a is gradually curved upward as at 24^b and a substantially deep latch notch is provided in the arm immediately inward of the abutment 29 between the latter and the curved 50 wall 24^b. By curving the upper side of the bar as at 24^b, the height of the arm at that point (with reference to Fig. 4) closely approaches the height of the keeper opening; and as the arm 24, by movement of the door, 55 approaches its open position the latch plate 33 is raised to substantially its uppermost position and finally drops by gravity downward into the latch notch holding the parts securely fixed together in a door-open position (Figs. 4 and 6). By employing a latch 60 plate of the structure shown and described, the keeper serves as a substantial background support for the latch member, rendering the latch and keeper as a whole capable of withstanding all shocks, jars, strains, stresses,

etc., exerted thereon by the arm due to the closing tendency of the door when subjected to gusts of wind, drafts, etc.

To unlatch the door, it is only necessary for the operator to pull downwardly on the chain 28 thereby raising the outer end of the unlatching bar 27 to engage the latching portion of the latch plate raising such latch plate until the upper edge of its opening is slightly above the top of the arm portion 24^b whereby the arm may be slid through both the latch and keeper openings for movement of the door to its closed position.

In Figs. 8 and 9 I show another form of gravity-operated latch member supported by 80 the keeper. In this form, the arm 37 and unlatching bar 38 are of substantially the same construction as the corresponding parts of the previously-described structure. The general form of the keeper 39 is also the same, 85 which keeper is provided with an opening 40 in its vertical web through which the arm slides. The horizontal web of this keeper is provided, near its free end, with a pair of depending ears 41 which are, preferably, 90 struck from the material of the keeper; but which, if desired, may be separately formed and secured to the keeper. The latch member 42 takes a U-shape with the outer ends of its U-arm pivotally secured as at 43 to the depending ears 41 so that its U-base portion 42^a 95 always tends to fall downwardly by gravity. When the door is in its closed position this latch member is held raised by the top of the U-arm and as the door moves into its fully 100 open position, the U-base portion 42^a of this latch member drops down into the notch 44 just inwardly of the abutment 45 thereby latching the door in its open position. To 105 unlatch the arm 37, the unlatching bar 38 (pivotally supported by arm 37) is operated 110 to swing its outer end upwardly to engage the latch member 42 thereby raising the latter out of the notch 44 so that the arm will slide freely through the keeper opening 40 115 as in the previously-described structure.

In Figs. 10, 11 and 12 I have shown another form of keeper 46 which supports a latch plate 47 which is constructed similarly to the latch plate 33. In this particular structure, 120 I provide positive means tending at all times to move the latch plate into its latching position. Specifically, the latch plate 47 is mounted upon the vertical leg of the keeper by means of headed pins 48, 49, the former being secured to the plate and sliding through an elongated slot 50 in the keeper and the latter being secured to the keeper and passing through an elongated slot 51 in the latch plate. This arrangement permits of vertical 125 reciprocation of the latch plate 47 by suitable pressure applied to the rivets or pins 48. To that end, the rear wall of the keeper supports hook-like pins 52, near its lower part, and similar pins 53 project rearwardly from the 130

plate-fastening pins 48, and these pins are connected together by coil springs 54 which, initially, are under slight tension so as to hold the latch plate 47 normally in the lowered latching position illustrated in Figs. 10 and 11. Although the door-holding arm is not illustrated in connection with this form, it is obvious that an arm similar to those previously described may be employed and as the door is moved to its full open position the latch plate will be snapped into and held yieldably in (by spring 54) the latching notch at the end of the arm. Means similar to that described in connection with the previous forms may also be employed for raising the latch plate 47 in opposition to the spring 54 for releasing the arm to close the door.

By reference to Fig. 12, it will be noted that the vertical web or leg of the keeper is provided with substantially parallel, vertical ribs 55 which provide in the rear of the keeper vertical inset spaces 56. I utilize these spaces for mounting the pins 48, 49 and spring 54 so as to shelter such structure from the weather and to prevent the same from being accidentally moved or injured. This same general vertical rib structure is, preferably, used in the forms previously described and such ribs serve to materially strengthen the vertical web of the keeper so as to better withstand the opening and closing stresses applied to the same through the door-holding arm.

While I have shown only three forms of structure embodying my invention, other changes in details and arrangement of parts may be made without departing from the spirit and scope of my invention as defined by the claims which follow.

40. I claim:

1. A door holder which comprises a keeper having an opening and adapted to be supported by the door frame, an arm slidably mounted in said keeper opening and adapted to be swingably secured to the door, a gravity-operated latch member adjustably supported by said keeper and having a part movable back and forth over said opening, the end of said arm having a square-faced notch in which said part is received and positively retained when the door is opened, and a member supported by said arm and independently operable to engage said part to move the latter out of said notch to permit said arm to slide through said keeper opening to close the door.

2. A door holder which comprises a keeper having vertical and horizontal web portions with an opening in its vertical web and having its horizontal web adapted to be secured to the door frame, an arm loosely and slidably mounted in said keeper opening and adapted to be swingably secured to the door for horizontal swinging movement, a latch member supported by said keeper for move-

ment back and forth over the upper end of said opening, the upper end surface of said arm having a substantially square-walled notch in which said latch member is received and retained against self-release when the door is opened, and a bar member pivotally supported by said arm and positively movable in one direction to engage said latch member to move the latter out of said notch to permit said arm to slide through said keeper opening to close the door.

3. A door holder which comprises a keeper having a vertical web with an opening and adapted to be stationarily supported by the door frame, an arm slidably supported in said keeper opening and adapted to be swingably supported at one end by the door, a gravity-operated latch member supported by said vertical keeper web for movement back and forth over the upper end of said keeper opening, an unlatching member supported by said arm and having an end part engageable with said latch member, said arm at its free end having a notch into which said latch member falls when said arm is moved to a door-open position, and means for operating said unlatching member to move said latch member out of said notch to permit closing movement of the door.

4. A door holder which comprises a keeper having a vertical web with an opening and also having a horizontal web adapted to be stationarily supported by the door frame, an arm slidably supported in said keeper opening and adapted to be swingably supported at one end by the door, a gravity-operated latch member supported by said vertical keeper web for movement back and forth over the upper end of said keeper opening, an unlatching bar pivotally supported by said arm and having an end part engageable with said latch member, said arm at its upper free end portion having a retaining notch into which said latch member moves when said arm is moved to a door-open position, and means for operating said unlatching member to engage its end part with said latch member to move said latch member out of said notch to permit closing movement of the door.

5. A door holder which comprises a keeper having a vertical web with an opening and adapted to be stationarily supported by the door frame, an arm slidably supported in said keeper opening and adapted to be swingably supported at one end by the door, a latch plate shaped similarly to said vertical web and having an opening of substantially the size of said keeper opening, elongated slots in said latch plate, means carried by said vertical web and engaging said slots for reciprocably supporting said latch plate on said vertical web with the part of said plate above its opening projecting normally down over the top of said keeper opening, said

arm at its upper free end having a substantially deep notch in which said part of said latch plate is adapted to be received when said arm is moved to its open position, and 5 unlatching means carried by said arm engaging said latch plate to move the latter out of said notch to release said arm.

6. A door holder which comprises a keeper having a vertical web with an opening and 10 adapted to be stationarily supported by the door frame, an arm slidably supported in said keeper opening and adapted to be swingably supported at one end by the door, a latch plate supported by said keeper for movement 15 toward and from said arm, said arm at its upper free end portion having a notch in which said plate is received when said arm is in its door-open position, spring means for normally holding said latch plate in a position 20 wherein it is over said keeper opening and in said notch, and means carried by said arm and adapted to engage said plate to move it out of said notch in opposition to said spring to release said arm, to permit the latter to slide through said keeper opening to a 25 door-closed position.

7. A door holder which comprises a keeper having a vertical web with an opening and adapted to be stationarily supported by the 30 door frame, an arm slidably supported in said keeper opening and adapted to be swingably supported at one end by the door, a latch plate reciprocably supported by said keeper with a part thereof adapted to slide 35 vertically back and forth over the top of said keeper opening, said arm at its upper free end portion having a notch in which said plate part is received when said arm is in its door-open position, spring means for normally holding said latch plate in a lowered position 40 wherein said part is over said keeper opening and in its notch-engaging position, and a member swingably carried by said arm and adapted to engage said plate part to move it out of said notch in opposition to said 45 spring to release said arm, to permit it to slide through said keeper opening to a door-closed position.

8. A door holder which comprises a keeper 50 having a vertical web with an opening and adapted to be stationarily supported by the door frame, an arm slidably supported in said keeper opening and adapted to be swingably supported at one end by the door, 55 said vertical web having laterally-spaced vertical ribs providing on its rear face inset vertical spaces or grooves, a latch plate approximating the shape of said vertical web mounted on the front face of the latter, 60 said plate having an opening corresponding to the keeper opening, said vertical web having elongated slots in the upper ends of said ribs and said latch plate having elongated slots in its lower portion adjacent said 65 vertical ribs, members carried by said plate

and engaging said web slots and members carried by said web and engaging said plate slots for reciprocably mounting said plate on said web, said arm having a notch in its upper, free end portion into which the portion of said plate above its opening moves when said arm is moved to its door-open position, spring means located in said vertical rib spaces for holding said plate yieldably in its notch-engaging position, and means for moving said plate to disengage it from said notch to permit closing of the door. 70

9. In structure of the class described, a keeper having a vertical web with an opening adapted to receive and support a door arm, 80 said web on opposite sides of said opening having vertical ribs pressed therefrom, a latch plate shaped similarly to said web and having ribs corresponding to said web ribs, and means for reciprocably supporting said plate on said web with their respective ribs 85 in nested relation.

10. In structure of the class described, a keeper having a vertical web with an opening adapted to receive and support a door arm, 90 said web on opposite sides of said opening having vertical ribs pressed therefrom, a latch plate shaped similarly to said web and having ribs corresponding to said web ribs, 95 means for reciprocably supporting said plate on said web with their respective ribs in nested relation, and spring means mounted in the spaces provided by said web ribs for yieldably holding said latch plate in its lowermost-reciprocable position. 100

In testimony whereof, I have subscribed my name.

LOUIS A. BITTORF.
